UNITED STATES PATENT OFFICE.

ELIE BLANCHETTE, OF LAWRENCE, MASSACHUSETTS, ASSIGNOR OF ONE-THIRD TO ATWOOD C. DELANO, OF LAWRENCE, MASSACHUSETTS, AND ONE-THIRD TO FRED E. GREGG, OF MARBLEHEAD, MASSACHUSETTS.

BRICK MACHINE.

Application filed September 19, 1924. Serial No. 738,621.

To all whom it may concern:

Be it known that I, ELIE BLANCHETTE, a citizen of the United States, residing at Lawrence, in the county of Essex and State 5 of Massachusetts, have invented certain new and useful Improvements in Brick Machines, of which the following is a specification.

This invention relates to brick machines and it consists in the novel features herein- 10 after described and claimed.

An object of the invention is to provide a machine of the character stated, which is of simple and durable structure, and which may be easily and conveniently operated by 15 hand, foot or power, forming a series of bricks simultaneously.

In the accompanying drawings:

Figure 1 is a front elevational view of the brick machine.

20 Figure 2 is a side elevational view thereof.

Figure 3 is a horizontal sectional view, thereof, cut on the line 3—3 of Figure 2.

25 Figure 4 is a fragmentary sectional view of the brick machine.

Figure 5 is a side elevational view of power means, which may be used for operating the brick machine.

30 Figure 6 is a perspective view of a partition wall, which may be used in the brick machine.

The brick machine comprises a stand 1 having a table 2, mounted on the same, the said table being provided at its inner edge with an upstanding flange 3, having spaced 35 recesses 4. A hopper 5 is mounted upon the upper rear portion of the stand and partition walls 6 are mounted for movement below the hopper and through the recesses 4 in the flange 3. The partition walls are 40 connected together by means of a rod 7, having its end portion slidably received in slots 8, provided at the sides of the stand 1. A shaft 9 is journaled at the intermediate portion of the stand and is provided with arms 10, having recesses 11, which receive the rod 7. Other arms 12 are fixed to the shaft 9, and are disposed at right angles to the arms 10. The forward ends of the arms 12 bear against the sides of levers 13, which 45 are pivoted upon a rod 14, at the upper forward portion of the stand, and spaced wall sections 15 are carried at the upper ends of the arms 13 and are adapted to be disposed

above the upper surface of the table 2. Springs 16 are connected at one end with the arms 13 and are connected at their other ends with the stand 1 and are under tension, with a tendency to hold the side edges of the arms 13 in engagement with the ends of the arms 12. A hand lever 17 is fixed to the 50 shaft 9.

It is apparent that when the upper end of the lever 17 is swung rearwardly, the shaft 9 is turned, whereby the arms 10 are rocked upon the said shaft, and the partition walls 6 are carried back under the hopper 5. The material of which the bricks are to be formed is passed through the hopper which is movable forward by hand and deposited upon the table 2 in the spaces between the 55 wall members 6. When the upper end of the lever 17 is swung in a forward direction, the shaft 9 is rocked, whereby the partitions 6 are moved to the position shown in Figure 4 of the drawing and the wall sections 15 are substantially vertically disposed at the forward edge of the table 2.

Arms 18 are pivotally mounted at the upper rear portion of the stand 1 and carry a series of plungers 19. Links 20 are connected at one end with the upper portion of the stand, and at the other end with the upper portion of the plungers 19, and serve to hold the plungers 19 in vertical positions, as best shown in Figure 2 of the drawings. 60

A pitman rod 21 may be connected at the upper portions of the plungers 19 and with a disc 22 mounted upon a power shaft 23 which is journaled above the stand, and the said power shaft and pitman may be used for forcing the plunger 19 down into the mold of which the table 2 forms the bottom wall. The foot treadle 24 is pivoted to the stand 1 and rods 25 operatively connect the treadle 24 with the arms 18 hereinbefore 65 described. An operator may apply his foot to the treadle 24 and depress the forward end thereof whereby the rods 25 are caused to move in a downward direction and the forward edge of the arms 18 are swung downwardly carrying with them the plungers 19 which operate upon the material in the mold sections and compress the said material in the form of bricks. Rods 26 are 70 pivotally connected at their upper ends with the arms 18 and their lower portions are

trained through eyes 27 provided at the ends of the stand 1. Collars 28 are mounted upon the rods 26 and coil springs 29 are interposed between the eyes 27 and the collars 28 5 and when pressure is removed from the outer end of the treadle 24, the springs 29 expand longitudinally and move the rods 26 in an upward direction, whereby the arms 18 are swung from a lowered to an elevated 10 position, such as shown in Figure 2 of the drawing.

Having described the invention, what is claimed is:

In a brick machine of the class described, 15 a table, a fixed wall at one edge of the table provided with a plurality of vertically disposed slots, a pivoted wall at the opposite edge of the table and provided with a plurality of slots, a plurality of partitions 20 able across the table through the slots of the walls, means for simultaneously sliding

the partitions across the table through the slots of the wall and swinging the pivoted wall to an upright position, said means comprising a shaft, arms extending from the 25 shaft, a rod extending through the ends of the partitions, a structure in which the shaft is journaled and provided with slots for receiving the rods, arms extending from the shaft and having slotted terminals receiving 30 the rods, other arms projecting from the shaft at an angle to the first arm, curved members extending from the pivoted wall and engageable with the second arm so that when the partitions are moved across the 35 table, said second arms will engage the members for swinging the pivoted wall to a vertical position, and spring means engaged with the members for normally urging the pivoted wall to a lowered position.

In testimony whereof I affix my signature. 40
ELIE BLANCHETTE.
